(57) **CLAIM**

The ornamental design for the cutting board and integrated slicing knife, as shown and described.

DESCRIPTION

FIG. 1 is a side view of the cutting board and integrated slicing knife.

FIG. 2 is a front view of the claimed design.

FIG. 3 is a rear view of the claimed design.

FIG. 4 is a top view of the claimed design.

FIG. 5 is a bottom view of the claimed design; and,

FIG. 6 is an isometric view of the claimed design.
